[57] CLAIM

The ornamental design for a pedestal extension dining table, as shown and described.

DESCRIPTION

FIG. 1 is a perspective view of a pedestal extension dining table showing my new design, with contrasting wood inlay in the top and pedestal;

FIG. 2 is a right side elevational view thereof, the left side elevation being a mirror image;

FIG. 3 is a front elevation thereof, the rear elevation being a mirror image;

FIG. 4 is a top plan view thereof;

FIG. 5 is perspective view of the table with extension leaves in place;

FIG. 6 is a right side elevation of the table with extension leaves, the left side elevation being a mirror image; and,

FIG. 7 is a top plan view thereof.

The bottom of the table is plain and unadorned.
